UNITED STATES PATENT OFFICE.

WILLIAM H. BAYNARD, OF BRAINTREE, AND FREDRICK W. EAGER, OF WINTHROP,
MASSACHUSETTS, ASSIGNORS TO HARRY H. BECKWITH, OF BROOKLINE, MASSA-
CHUSETTS.

SHOE-HEATER.

1,358,695.

Specification of Letters Patent. Patented Nov. 16, 1920.

Application filed September 21, 1917. Serial No. 192,569.

To all whom it may concern:

Be it known that we, WILLIAM H. BAY-
NARD and FREDRICK W. EAGER, citizens of
the United States, residing, respectively, at
5 Braintree, in the county of Norfolk and
State of Massachusetts, and at Winthrop, in
the county of Suffolk and State of Massa-
chusetts, have invented new and useful Im-
provements in Shoe-Heaters, of which the
10 following is a specification.

This invention has relation to apparatus
for softening the stiffened portions of foot-
wear preparatory to end lasting. In ac-
cordance with modern practice, it is cus-
15 tomary to employ as the toe box or as the
counter stiffener a shaped blank of fibrous
material saturated or impregnated with a
stiffening compound of an asphaltic or resi-
nous nature, which may be softened at a
20 temperature below that at which leather
would be injured. So far as we are aware,
it has never heretofore been proposed to
heat or soften the stiffener at more than one
25 end of the shoe only. In the operation pre-
paratory to end-lasting the shoe or other
form of footwear, it is desirable to supply
sufficient heat to effect the softening of the
stiffening compound and also to supply a
30 certain amount of warm or heated moisture
to moisten the leather portions of the shoe.
In the apparatus which has heretofore been
employed, it has been impossible to secure
the desired heat of radiation and the proper
35 amount of moisture without securing a heat
which is dangerous for the leather.

This invention has for its primary object
the provision of a shoe heater in which it
is possible to secure within the space into
40 which the shoe is heated sufficient moisture
for softening the leather at a relatively low
temperature. We regard the optimum tem-
perature as approximately 170° to 185° F.
depending upon the period of time to which
45 the shoe may be subjected to the heat.

Another object of the invention is to pro-
vide a heater by which both the toe box
and the counter stiffener may be heated
simultaneously, thereby greatly shortening
50 the time required for preparing the shoe
for end-lasting.

Still another object of the invention is to
provide a heater in which there shall be a
minimum amount of moisture escaping into
the atmosphere in which the operator is

working, thereby greatly improving the 55
conditions under which the operator works
and lessening the danger of injury to his
health. The invention has further to pro-
vide a heater in which the degree of tem-
perature and the amount of supplied mois- 60
ture may be separately controlled, by which
the products of condensation from the mois-
ture may be removed prior to the delivery
of the vapor to the moistening chamber in
which the current of moisture or vapor is 65
directed to those portions of the shoe which
it is desired to heat and moisten, and by
which certain other advantages are secured,
all as will be pointed out in the following
70

Referring to the accompanying drawings
which illustrate one embodiment of our in-
vention, to the details of construction, how-
ever, we desire it to be understood that the
invention is not limited, —

Figure 1 represents a plan view of the
heater.

Fig. 2 represents a front elevation of the
same.

Fig. 3 represents a side elevation.

Fig. 4 represents a vertical section through
one unit of the heater.

Fig. 5 represents a section on the line 5—5
of Fig. 4.

Fig. 6 represents a section on the line 6—6 85
of Fig. 5 looking in the direction of the
arrow.

The heater, considered as a whole, com-
prises a plurality of vapor units, one for
each shoe, and the units may be all arranged 90
within a common housing of suitable con-
struction. Ordinarily we employ a housing
adequate in size to receive two units or a
multiple thereof. In the embodiment of the
invention which is illustrated upon the 95
drawing, the housing comprises a bottom
plate 10 which slopes from its front to its
rear end at a relatively slight inclination
but sufficient to cause the products of con-
densation to flow toward the rear end. 100
This plate is approximately pan-shaped and
its front portion is provided with raised
side walls 11. There is a rear wall 12, a
front wall 13 and side walls 14. The front
wall 13 is removable and is held in place by
105 fastenings 15 secured to inturned flanges
on the front end of the side walls. The
front wall is also provided with a plurality

of semi-circular openings or apertures 16 adequate in size to receive the toe portion of a shoe, as indicated in dotted lines in Fig. 4. There is one opening for each vapor 5 unit of the heater. The top wall 17 of the housing is peaked like the roof of a house, and is removable, being provided with flanges which lap within the front, rear and side walls of the housing, and are secured 10 thereto by suitable screws or fastenings 18. From the peak of the cover leads a stack 19 like a stove pipe, which is preferably connected to the flue of a chimney or which is carried to a sufficient elevation to secure the 15 proper draft.

From this description, it will be seen that we have provided a housing which is substantially the shape of a rectangular box in plan view with an eduction conduit leading 20 from the peak of the cover and with apertures in its front wall for the reception of the fore parts of the shoes to be treated. The pan or bottom plate 10 projects forwardly from the box and is utilized to support 25 the heating element for the counter stiffener. It should be noted in Fig. 4 that the lower edge of the front wall 13 is slightly elevated above the plate 10 so as to permit products of condensation to flow to 30 the rear portion of the pan where they pass out through a drip pipe 20 leading therefrom as shown in Figs. 2 and 4. Placed within the housing there is a steam coil 21, consisting of straight pipes connected by 35 elbow couplings and arranged so that there is a series of horizontal pipes arranged in a horizontal plane immediately above the plane of the tops of the openings 16, and a plurality of pipes immediately below the 40 horizontal plane of the lower walls of said openings 16, as best shown in Fig. 4. The coil may consist of as many convolutions as desired. This coil is placed relatively close to the front wall and the stack 19 is directly 45 above this coil. Live steam under pressure is fed to the coil by a pipe 22, said pipe communicating with a main steam pipe 23 leading from the boiler. At the other end of the coil there is an outlet pipe 24 provided with 50 a valve 25 for maintaining the desired pressure in the coil and insuring the desired heat of radiation therefrom. From what has been described, it is now apparent that, when a shoe is inserted in one of the apertures 55 16, the stiffened toe box blank lies directly above the lower pipes of the coil where it is in position to receive the heat radiated therefrom, so that it may be subjected to the desired temperature necessary 60 to effect the softening of the stiffening compound.

For each shoe opening in the housing, we employ a separate moistening chamber or unit which is preferably so disposed as to 65 provide a shield between the top of the end

of the shoe and the upper pipes of the coil so as to prevent an over-heating of the end of the shoe and also for another purpose which will be described. Each moistening unit consists of a box which is provided 70 with side walls 26, 26, a rear end wall 27, a top wall 28 which extends across only the rear portion of the side walls, and a bottom wall 29 which extends across the box at the rear portion thereof. The side walls 75 are shaped as shown in Fig. 4, so that the box as a whole is inclined upwardly and rearwardly, and so that the side walls may at their front ends rest upon the bottom pipes of the coil. At its rear portion, the 80 box is provided with an upright partition 30 to provide an expansion chamber 31. The partition does not extend entirely across the box, as illustrated in Fig. 5, but is provided with forwardly extending walls 32 85 which parallel the side walls 26 but which terminate short of the front ends of the said side walls. The side walls 26, as shown in Fig. 5, are provided with inwardly and rearwardly extending wings 33, which overlap the front ends of the extensions 32 of the partition so as to provide a tortuous passageway 34 from the expansion chamber 31 to the front portion of the shoe chamber 35. The wall or partition 30 is provided 90 with a plurality of ports 36, and an inclined cross plate 37 extends from the partition 30 at a point above the ports 36, forwardly and downwardly, and is connected or formed integrally with the bottom wall 29 100 of the unit. The plate 37 is also provided near its front lower end with a plurality of ports 38 which are in a horizontal plane below the shoe when the latter is inserted in the shoe opening into the shoe chamber of 105 the unit. The ports 38 are thus to be located as to direct a stream of vapor against the toe box of the shoe, and, with the vapor which passes from the expansion chamber 31 through the tortuous passage 34 into 110 the shoe chamber, to fill the chamber with vapor or moisture. The front portions of the side walls 26 project upwardly above the plane of the top wall 28 to receive and support a cover or shield 39 which slants downwardly and rearwardly from a line adjacent the front wall of the housing above the shoe opening 16 to a point just in front of the front edge of the top plate 28 so as to leave an elongated port 40 for the emission of 115 vapor from the shoe chamber into the interior of the housing. The unit, as thus described, comprising the side walls, the rear end wall, the bottom wall, the top wall 28, and the shield 39, is removable bodily from 120 the housing, and it comprises the rearwardly located expansion chamber and the forwardly located shoe chamber which is open at its front end and which terminates at the front wall of the housing in position to 125 130

receive a shoe inserted through the shoe opening 16 in the housing. This shoe chamber at its front and lower portion is open so as to interpose no obstruction to the heat 5 of radiation from the lower pipes of the heater or coil, but its top is closed so as to interpose a shield between the top pipes of the coil and the shoe which may be inserted in the chamber. Moisture is supplied 10 to the expansion chambers by a pipe 41 which is inserted in one end of the housing and extends entirely therethrough, and which is capped at its other end as indicated at 42. This pipe, which is easily removable by unscrewing it from the elbow 43, extends through the expansion chambers 31, and within each chamber is provided with a relatively small port 44 which opens toward the rear of said chamber so as to 15 20 direct the vapor toward the rear upper portion of said chamber. This vapor pipe is provided with a valve 45 and is connected to a T coupling 46 which is in turn connected by a pipe 47 with a vapor chest indicated as a whole at 48. This chest may be of any suitable shape and dimensions. As illustrated, however, it is cylindrical in form with removable upper and lower heads 49, 50. Live steam is delivered to the lower 25 30 portion of this vapor chest by a branch pipe 51 leading from the main steam pipe 23, said pipe 51 being provided with a valve 52. The vapor chest 48 is sufficient in size to permit the steam entering thereinto to 35 expand and vaporize before the vapor is conducted from the upper end of the chest through the pipe 41 to the expansion chambers of the several units in the housing. By permitting the vapor to expand within 40 the chambers 31 before it is admitted to the shoe chamber of the unit, we insure the cooling of the vapor and its delivery to the shoe chamber at the desired temperature. The steam entering the chest is controlled 45 by an independent valve so that its volume is easily regulated, thereby insuring the delivery of the proper amount of vapor to the expansion chambers and the shoe-receiving chambers of the vapor units. The products 50 of condensation are delivered from the chest 48 through a drip pipe 53 provided with a valve 54.

From the foregoing description, it will now be apparent that it is possible to regulate 55 the temperature of the dry heating coil 21 quite independently of the temperature and volume of vapor delivered to each shoe chamber, and that, on the other hand, the volume and temperature of the vapor so delivered may be regulated and controlled 60 quite independently of the temperature of the heating coil. Consequently we are able, according to the character of the material of the shoes to be treated, to vary the temperature 65 of the heater and to vary the supply

and the temperature of the vapor so as to soften the stiffening compound of the toe box without injuring the other portions of the shoe.

In this connection, we desire to call attention to the fact that we secure a circulation through the housing. This is accomplished by the provision of the stack 19, but, in order that there shall be a constantly ascending stream of heated air and moisture passing through the stack, the upper pipes of the coil are utilized in securing this result. The stack is located over them, and the air, which enters the shoe openings in the housing, is heated sufficiently to cause it to rise 75 through the stack and insure the desired circulation, all without injury to the shoe which is inserted in the openings. The shoe does not fill the opening and consequently there is a constant stream of air flowing in 80 around the shoe which is sufficient to temper the heat from the lower pipes of the coil to prevent over-heating and also to insure the circulation through the housing. As a result of the construction and arrangement 85 described, there is substantially no vapor escaping from the shoe openings 16 when the heater is in operation. In this way, we have remedied one of the most serious defects incident to the process of softening stiffened 90 toe boxes as heretofore practised. Ordinarily, in a factory in which the toe boxes are being steamed and heated, the atmosphere is filled with vapor to such an extent as to endanger the health of the operators. This 95 condition we have obviated to a very great extent.

In addition to heating the fore part of the shoe, we also provide, for each unit, a separate instrumentality for moistening and 105 softening the counter stiffener. Each such device consists of a hollow metallic case 60 which is in plan view of such dimensions as to fit within the depending edges of the counter stiffener of a shoe resting thereon, as 110 shown in Fig. 4. Each heel heater or case is provided with legs or supports 61 which rest upon the forward extension of the bottom plate 10. The top wall of the heel heater is imperforate, but the side and rear 115 wall is provided with a plurality of minute ports 62 for the escape of vapor conducted to the interior of the heater and so as to direct that moisture against the depending edge or margin of the counter stiffener. 120 Moisture is supplied to the several heel heaters by a main pipe 63 which is connected to the T coupling 46, as shown in Figs. 1, 2 and 3. Said pipe 63 is provided with a valve 64 by which the vapor from the vapor 125 chest may be controlled. The pipe 63 is provided with a plurality of couplings 65, and it projects into the rear and bottom portion of the housing so as to lie in a plane below the horizontal plane of the bottom or lower 130

pipes of the heating coil 21. To each coupling there is connected a forwardly projecting pipe 66 which extends through the front wall of the housing and terminates in a packed collar 67. This pipe 66 is located directly below one of the vapor units previously described. From the end wall of each heel heater projects a pipe 68 provided with suitable elbows, so that its end may 10 project through the packed collar 67 into one of the pipes 66. A slip or sliding coupling is thus provided between each pipe 68 and its associated pipe 66 so as to permit the heel heater to be adjusted toward and from 15 the front wall of the housing to locate the heel heater in proper position to receive the heel portion of a shoe of the size undergoing treatment. Naturally each heel heater is located in front of one of the shoe openings 16 20 in the front wall of the housing and at the proper elevation so as to assist in supporting the shoe approximately horizontally as shown in dotted lines in Fig. 4.

Of course it will be understood that, if 25 desired, the heel heaters may be totally disconnected from the apparatus, in which case the valve 64 is kept closed, or the entire pipe 63 may be disconnected from the chest and the end of the T coupling plugged. 30 Even though the heel heater be not used for softening the counter stiffener, by cutting off the supply of vapor thereto, it may be utilized merely as a support for the rear end of the shoe. The case 60 of course may be 35 supplanted by any other form of support which will hold the shoe horizontally. If desired, the pipes 68 at the ends of the housing may be connected by a cross piece which will serve to support the heel ends of the 40 shoes inserted in all of the shoe openings, and such an expedient when once suggested is so simple as not to require illustration. The pipes 66 constitute guides for the heel supporting (and heating) members 60. 45 The condensation products from the heel heater and the expansion and shoe-receiving chambers of the vapor units or boxes in the housing drip to the inclined supporting plate or pan and are conducted away by the 50 drip pipe 20. The pan serves as a support common to the toe-heating and moistening instrumentality and the heel heater.

Having thus explained the nature of our 55 said invention and described a way of making and using the same, although without attempting to set forth all of the forms in which it may be made, what we claim is:

1. A shoe heater comprising a housing having an aperture to receive the shoe, 60 means for supplying vapor to the interior of said housing, a stack leading from said housing, and means for creating a draft upwardly through said stack.

2. A shoe heater comprising a housing 65 having a peaked cover, and having a shoe

aperture, means for supplying vapor into said housing, a stack leading from the peak of said cover, and a heating element located in said housing below said stack to create a draft upward through said stack. 70

3. A shoe heater comprising a housing having an aperture to receive a shoe, and a heating coil within the housing adjacent the aperture to receive the shoe in the convolutions of said coil. 75

4. A shoe heater comprising a housing having an aperture in its front wall to receive a shoe, and a heating coil within the housing and having its convolutions above and below the horizontal planes of said aperture to receive the shoe. 80

5. A shoe heater comprising a housing having an aperture in its front wall to receive a shoe, a heating coil within the housing and having its convolutions above and below the horizontal planes of said aperture to receive the shoe, and a shield below the upper portions of the convolutions to protect the shoe from heat radiated thereby. 85

6. A shoe heater comprising a housing 90 having an aperture in its front wall to receive a shoe, a heating coil within the housing and having its convolutions above and below the horizontal planes of said aperture to receive the shoe, a shield below the upper portions of the convolutions to protect the shoe from heat radiated thereby, and a stack leading from the upper portion of the housing and above the said heating coil. 95

7. A shoe heater comprising a housing 100 having an aperture to receive the shoe, a plurality of heating elements located below the horizontal planes of the aperture to radiate heat to a shoe inserted in said aperture, and means for introducing vapor into 105 the housing and liberating it above said heating elements and below the horizontal planes of said aperture.

8. A shoe heater comprising a housing, a heating element for supplying heat but 110 no moisture in said housing, means for supplying vapor into said housing, and means for cooling said vapor prior to its liberation in said housing.

9. A shoe heater comprising a housing, a 115 heating element therein for supplying heat but no vapor, a steam supply pipe, a vapor chest connected thereto and having an outlet, and means for conducting vapor from said chest to said housing. 120

10. A shoe heater comprising a housing having a shoe-receiving aperture, a heating element in said housing, a source of steam supply, a vapor chest connected thereto outside the housing and having a vapor outlet, 125 and means for conducting vapor from said chest into said housing.

11. A shoe heater comprising a housing having a shoe-receiving aperture, a heating element in said housing, a steam pipe lead- 130

ing into said housing, and an expansion chamber in said housing communicating with said pipe and having openings for liberating vapor into said housing.

5 12. A shoe heater comprising a housing having a shoe-receiving aperture, a heating element in said housing, a vapor element in said housing having an opening registering with said aperture so as to receive said shoe, 10 and means to supply vapor thereto.

13. A shoe heater comprising a housing having a shoe-receiving aperture, a heating element in said housing, a vapor element in said housing having an opening registering 15 with said aperture so as to receive said shoe and arranged to direct the vapor against the shoe, and means for supplying vapor to said element.

14. A shoe heater comprising a housing 20 having a shoe-receiving aperture, a heating element in said housing, a vapor element in said housing having an opening registering with said aperture so as to receive said shoe, said element having an expansion chamber 25 and openings leading therefrom, and means for supplying vapor to said expansion chamber.

15. A shoe heater comprising a housing 30 having a shoe-receiving aperture, a heating element in said housing, a vapor element in said housing having a shoe-receiving chamber adjacent said aperture, an expansion chamber communicating with said shoe-receiving chamber, and means for supplying 35 vapor to said expansion chamber.

16. A shoe heater comprising a housing having a shoe-receiving aperture, a vapor element in said housing having a chamber adjacent said aperture and adapted to receive the shoe projected into said aperture, 40 and means for supplying said chamber with vapor.

17. A shoe heater comprising a housing having a shoe-receiving aperture, a vapor element in said housing having a chamber adjacent said aperture and adapted to receive the shoe projected into said aperture, a heating element in the housing arranged 50 to radiate heat into said chamber, and means for supplying vapor into said chamber.

18. A shoe heater comprising a housing having a shoe-receiving aperture, a vapor element in said housing having a chamber adjacent said aperture to receive the shoe, means for supplying said chamber with vapor, and a vapor expansion chamber communicating with the shoe-receiving chamber, means for supplying vapor to said expansion chamber, and a heating element arranged to radiate heat into said shoe-receiving chamber.

19. A shoe heater comprising a housing having a shoe-receiving aperture, and a vapor element therein having a shoe-receiving

chamber adjacent said aperture, a vapor-receiving chamber, and openings therefrom into the shoe-receiving chamber.

20. A shoe heater comprising a housing having a shoe-receiving aperture, and a vapor element therein having a shoe-receiving portion adjacent said aperture, a vapor-receiving chamber, and means for conducting vapor from said chamber into said shoe-receiving portion and directing it against the sides and the end of the shoe.

70 21. A shoe heater comprising a housing having a shoe-receiving aperture, and a vapor element therein having a shoe-receiving portion adjacent said aperture, a vapor-receiving chamber, means for conducting vapor into the sides of said shoe-receiving portion, and means for conducting vapor to deliver it in said shoe-receiving portion beneath a shoe inserted in said aperture.

80 22. A shoe heater comprising a housing having a shoe-receiving aperture, and a vapor element therein, said element comprising a shoe-receiving chamber having an open end, side walls and a top wall and having an outlet for vapor, and a closed expansion chamber having ports for conducting vapor into the shoe-receiving chamber.

90 23. A shoe heater comprising a housing; a vapor element comprising a shoe-receiving chamber having an open end, side walls and a top wall and having a vapor outlet, and a closed vapor expansion chamber having ports for delivering vapor to said shoe-receiving chamber; means for supplying vapor to said expansion chamber; and a heating element at the bottom of said shoe-receiving chamber to radiate heat to a shoe inserted therein.

95 24. A shoe heater comprising a housing having a plurality of shoe-receiving apertures, a heating element therein, and a plurality of shoe-receiving vapor chambers in said housing, one for each opening.

105 25. A shoe heater comprising a housing having a plurality of shoe-receiving apertures, a heating element therein, a plurality of vapor units in said housing, one for each opening, each unit being arranged to receive a shoe and to contain vapor, and means for supplying vapor to said units.

110 26. A shoe heater comprising a housing having a plurality of shoe-receiving apertures, means for supplying heat to the interior of said housing adjacent said apertures, and a separate element within said housing for each aperture for inclosing the shoe inserted therein in an atmosphere of vapor.

120 125 27. A shoe heater comprising a housing having a plurality of shoe-receiving apertures, a heating element in said housing common to all the shoes inserted in the apertures, a separate shoe-receiving chamber for each aperture and arranged in the housing

- 6
- to receive the shoe end inserted in such aperture, and means for supplying vapor to said chambers.
28. A shoe heater comprising a housing having a plurality of shoe-receiving apertures, a plurality of shoe-receiving chambers in said housing, one for each aperture to inclose the shoe end inserted in such aperture, means for supplying said chambers with vapor, and heating means arranged to radiate heat into such chambers.
29. A shoe heater comprising a housing having a plurality of shoe-receiving apertures, a plurality of shoe-receiving chambers in said housing, one for each aperture to inclose the shoe end inserted in such aperture, means for supplying said chambers with vapor, and a steam-heating element arranged to radiate heat into all of said chambers.
30. A shoe heater comprising a housing having a plurality of shoe-receiving apertures, a plurality of shoe-receiving chambers in said housing, one for each aperture to inclose the shoe end inserted in such aperture, means for supplying said chambers with vapor, and a steam-heating coil in said housing having its pipes arranged above and below said chambers, said coil being arranged to radiate heat into said chambers.
31. A shoe heater comprising a housing having a plurality of shoe-receiving apertures, an element for supplying heat by radiation in said housing, and means within said housing for localizing and confining an independent atmosphere of vapor adjacent each aperture for the shoe end inserted therein.
32. A shoe heater comprising a housing having a plurality of shoe-receiving apertures, a stack leading from the top of said housing, a plurality of vapor chambers in said housing each open to receive a shoe inserted in one of the apertures; means for supplying heat to said chamber, heating means arranged to create an upward draft through said stack, and means for supplying vapor to said chambers.
33. A shoe heater comprising a housing having an aperture to receive the toe end of a shoe, means for supplying heat and vapor in said housing, and a heater on which the heel end of an upright shoe may be supported, arranged in operative relation to the housing.
34. A shoe-heating instrumentality for simultaneously heating both ends of a shoe, comprising a toe heater and a heel heater, each arranged to supply heat and moisture, and a common support for said toe and heel heaters, said heel heater being constructed and arranged to be embraced by the flange of the counter stiffener of the shoe.
35. A shoe-heating instrumentality comprising a housing having an aperture to re-

ceive the toe end of the shoe, means for supplying heat and vapor to the housing, a heel heater in line with the aperture, constructed and arranged to fit within the flanges of a counter stiffener, and means for supplying heated vapor to said heel heater, said heel heater having ports for the emission of vapor against the inner edges of the said counter stiffener of the shoe.

36. A shoe-heating instrumentality comprising a housing having a shoe-receiving aperture, means for supplying heat and vapor to said housing, a heel supporting and heating member, constructed and arranged to engage the heel end face of the shoe sole, and adjustable means connecting said member to said housing.

37. A shoe-heating instrumentality comprising a housing having a shoe-receiving aperture, means for supplying heat and vapor to said housing, a guideway in said housing, and a heel-supporting member movable along said guideway toward and from the back of said housing and having a flat face on which the heel end of the sole may be placed.

38. A shoe-heating instrumentality comprising a housing having a shoe-receiving aperture, means for supplying heat and vapor to said housing, a hollow heel heater arranged in line with said aperture, and a conduit comprising telescopic sections connected to said vapor-supplying means and to said heater and arranged to permit adjustment of said heater toward and from said aperture.

39. A shoe-heating instrumentality comprising a pan, a housing thereon, having a shoe-receiving aperture, means for supplying heat and vapor to said housing, a heel supporting and heating member resting on said pan in line with said aperture, and means for supplying vapor to said member.

40. A shoe-heating instrumentality comprising a housing having a shoe-receiving aperture, means for supplying heat and vapor to said housing, a hollow heel heater having ducts for the emission of vapor and arranged in line with said aperture, a stationary vapor supply pipe, and a pipe connected to said heater and telescoping with said supply pipe.

41. A heater for softening the stiffened counters of shoes, comprising a member approximating the shape of a flat heel, shaped and arranged to fit within the margin of the counter of an unlasted shoe and support the heel end of the sole thereon, and means for heating the same.

42. A heater for softening the stiffened counter of a partially formed shoe, comprising a hollow metallic casing arranged and adapted to be embraced by the projecting flange of the counter, said casing having a top wall to support the heel end of

the shoe, and having a perforated side and end wall, and means for supplying vapor to the interior of said casing.

43. A heater for softening the stiffened counters of shoes, comprising a hollow metallic member shaped and arranged to fit within the margin of the counter stiffener of an unlasted shoe, and having an upper surface for engaging and supporting the heel end of a shoe, and means for supplying vapor thereto.

44. A heater for softening the stiffened counters of shoes, comprising a hollow metallic member shaped and arranged to fit within the margin of the counter stiffener of an unlasted shoe and to engage the heel end of the sole of such shoe, and having lateral ports for the emission of vapor against the said stiffener, and a conduit for supplying vapor to said member.

45. A shoe heater comprising a housing

having a plurality of shoe-receiving apertures, a steam coil for radiating heat in said housing, a valve for regulating the passage of steam to said coil, a pipe for supplying vapor to said housing, a main steam pipe connected to said steam coil, a vapor chest, a conduit connecting the said chest with said main steam pipe, and a valved connection between said vapor chest and said vapor pipe.

46. A device for softening the counter stiffeners of shoes, comprising a hollow member approximating the shape of a flat heel, means for supporting said member to permit the heel end of the sole of a partially finished shoe to rest thereon, and means for heating said member.

In testimony whereof we have affixed our signatures.

WILLIAM H. BAYNARD.
FREDRICK W. EAGER.
